Primary Examiner — Michelle E. Wilson*Assistant Examiner* — Ania Aman(74) *Attorney, Agent, or Firm* — Brick Gentry PC; Brian J. Laurenzo; Jessica L. Susie(57) **CLAIM**

The ornamental design for a fire pit, as shown and described.

DESCRIPTION

FIG. 1 is a perspective view of the fire pit.

FIG. 2 is another perspective view of the fire pit of FIG. 1.

FIG. 3 is a top view.

FIG. 4 is a front view.

FIG. 5 is a cross-sectional view taken along the line 4-4 of FIG. 4; and,

FIG. 6 is a bottom view.

The broken line shown in the drawings are for the purpose of illustrating portions of the article and form no part of the claimed design.
